UNITED STATES PATENT OFFICE.

JOHN K. SHAW, OF MINNEAPOLIS, MINNESOTA, ASSIGNOR TO C. F. DAHLBERG, OF ST. PAUL, MINNESOTA.

PROCESS OF AND APPARATUS FOR MAKING FIBER BOARDS.

Application filed April 6, 1920, Serial No. 371,568. Renewed January 9, 1923.

To all whom it may concern:

Be it known that I, JOHN K. SHAW, a citizen of the United States, residing at Minneapolis, in the county of Hennepin and 5 State of Minnesota, have invented certain new and useful Improvements in Processes of and Apparatus for Making Fiber Boards; and I do hereby declare the following to be 10 a full, clear, and exact description of the invention, such as will enable others skilled in the art to which it appertains to make and use the same.

This invention relates to a process of and 15 an apparatus for interlacing fibers preparatory to making fiber boards, and has for its object to provide a method and a means which will be more efficient in action and less expensive to operate than those heretofore proposed.

20 With these and other objects in view the invention consists in the novel steps and combinations of steps constituting the process and in the novel parts and combinations of parts constituting the apparatus, all as 25 will be more fully hereinafter disclosed and particularly pointed out in the claims.

This application is an improvement over 30 my copending application, Serial Number 368,990 filed Mar. 26, 1920, and entitled 35 Process of and apparatus for making fiber boards.

Referring to the accompanying drawings forming a part of this specification in which like numerals designate like parts in all the 35 views:—

Figure 1 is a diagrammatic sectional view of an apparatus made in accordance with this invention;

Figure 2 is a view showing the normal positions of the wires in the belt before stretching;

Figure 3 is a view showing the effect of stretching on the wires;

Figure 4 is a diagrammatic view illustrating the disposition of the individual fibers before reaching the traveling surface;

Figure 5 is a view similar to Figure 4 illustrating the action of the traveling surface upon the individual fibers; and

50 Figure 6 is a diagrammatic sectional view of a fiber board made in accordance with this invention.

Referring to Figure 1, 1 indicates any suitable tank for holding the water and

fibers, 2 the bottom of said tank, 3 an inclined false bottom located above the bottom 2, 4 a roll or drum near the lower end of said false bottom 3, 5 a plurality of supporting rolls, 6 a guide and compression roll adjustable on the slide, or other movable means 7, 8 a guide roll similar to the roll 4, and 9 a guide and tensioning roll and adjustable on the means 10. Passing over the rolls just mentioned is the endless foraminous belt or surface 11, conveniently made of wire cloth, and having the oppositely moving portions or runs 12 and 13.

Between the runs 12 and 13 is located the water outlet 15, provided with the controlling means or gate 16 which may be suitably manipulated as by the handle or other device 17.

Coating with the foraminous surface or belt 11, and in close proximity thereto as regards one portion thereof, is the foraminous belt 18, passing over and around the series of guide rolls 19, 20, 21, 22, 23 and 24. Said belt 18 also passes over the compression and guide roll 25 coating with 80 the compression roll 6, and adjustably mounted on the movable means 26. 27 represents a tension and guide roll, adjustably mounted on the means 28, and 29, an outlet for the water passing through the belt 85 18, controlled by the gate 30 and adjustable through the handle 31. 32 and 33 represent suitable water seals made of flexible material for the belts 11 and 18 respectively.

35 represents a channel or passage for 90 water and fibers which may be maintained at any desired hydrostatic head 36, 37 an opening from the channel 35 into the tank space 38, and 39 a top or partition separating said space 38 from the remainder of the tank. 40 represents a second channel for water and pulp fibers, 41 the head thereof, 42 an opening from said channel into the tank space 43, and 44 a partition which with the partition 39 serves to separate said space 43 from the rest of the tank, 45 represents a third channel for water and fibers having a head 46, 47 an opening into the tank space 48, and 49 a partition coating with the partition 44 to segregate said 100 space 48 from the remainder of the tank.

In machines of this character it is necessary to have the aggregate area of the

meshes of the traveling surface sufficiently large to carry away the waste water fast enough to properly interlace the fibers. But if the mesh is fine enough to properly stop the stock, the screen must be very long to furnish the required aggregate mesh area. For example, said mesh, if fine enough to stop the fibers, should be, say, about twenty to the square inch under ordinary conditions; and in that case the endless belt 11 would be about 57 feet long. But when this great length of screen is employed with such a fine wire mesh, the strain on the screen is almost sure to so pull the strands, as to cause the mesh to change from the pattern shown in Figure 2 to that shown in Figure 3. This pulling action so changes the pattern on the paper or other material produced, that the resulting product is damaged. On the other hand, when the screen is shortened to about say 17 feet or somewhat longer in order to avoid this change of pattern, the mesh of a wire cloth must be so increased that the stock is apt to pass through the screen too fast if we are to get rid of the water with the desired speed for a good interlacing of the fibers.

To avoid these objections, in carrying out this invention, I provide the screen 11 of a relatively large mesh, say about 14 to the square inch, and find that its wire strands are sufficiently strong to prevent any objectionable pulling when said screen is made very much shorter than 57 feet, but, of course, meshes of this size do not stop the stock and interlace them as efficiently as could be desired. Accordingly, I locate inside said screen 11, a relatively short endless screen 100, which has a mesh of about 20 to the square inch, and which conveniently passes around the rollers or drums 4 and 101 as illustrated.

It will be understood that this invention may only flow water through screen 11, the opening 29, in that case being cut off by the gate 30, and when such is the case, only one endless belt 100 will be required. On the other hand, water may be flowed simultaneously through the screens 11 and 18, and in such latter case the screen 18 may in some cases be sufficiently short to enable one to use a 20 mesh wire cloth. In such cases, again only one screen 100 will be necessary. But, other cases may arise in which I will need a 14 mesh cloth in screen 18, and in that event I provide a second wire cloth screen 103 of 20 mesh which conveniently passes around the rollers 22 and 24. In either or both cases, said screens 100 and 103 of a relatively fine mesh, serve to stop the fibers passing the screens 11 or 18, and thereby cause more or less fibers to stop or interlace on the coarser meshes of said screens 11 or 18. These said last mentioned fibers soon pass beyond the

regions or positions of said screens 100 and 103, and thus serve to stop other fibers, which would ordinarily pass entirely through the relatively coarse meshes of said screens 11 and 18, all as will appear more fully hereinafter.

The operation of this machine will be understood from what follows:

It is preferred to use long fibers but of course fibers of any usual length may be employed. Said fibers by reason of the direction of flow of the water through the belt 11, or surface 13, will be brought into positions more or less parallel to each other, and more or less perpendicular to the line of travel of the surface 13, while at the same time all of said fibers will occupy positions more or less staggered with relation to their neighbors as shown. Accordingly, a large percentage of the forward ends 61 of the first portions of said fibers will first pass through said surface 13, as indicated in Figure 4, but will be stopped, and carried along by the belt 100 from the positions shown in Figure 4 to those shown in Figure 5, wherein the rear ends 62 of said fibers are illustrated as having lagged behind the front ends 61, in the water, so that the front row of said fibers have assumed a somewhat curved or bent shape. Owing to the stoppage of the fibers by the belt 100, the second row, or those fibers 63 immediately following, and which have not reached the surface 13, but have reached the rear ends 62 of the fibers 60, are now forced by the oncoming water to contact at their forward ends against the curved fibers 60. This action causes the mass of fibers to interlace on the relatively large meshes of the surface 13, and to sufficiently close said meshes to cause succeeding fibers in the chamber 43, to likewise interlace on said surface without the aid of the finer meshed surface 100. In other words, said fibers 63, originally, due to their parallel positions as shown at 63 in Figure 4, were more or less staggered or interlaced with the other fibers 60, before the latter became curved; and it is evident that this interlacing or entangling action between the fibers 60 and 63 will be enhanced or increased by the oncoming water after the surface 13 becomes covered with fibers in the manner just stated, and after said curvature takes place. It results from the actions just described that said fibers 63 in chamber 43, become themselves more or less curved, as indicated in Figure 5, due to the transverse movement of the fibers 60, and that a third row of fibers 64 which are also interlaced or staggered with the fibers 63, will become in time curved and entangled with the fibers 60 and 63 that have preceded said fibers 64, even though the meshes of surface 13 are so large as to permit, under normal conditions, said fibers to pass. It thus results that owing to

the presence of the finer meshed belt 100 and to the floating of the fibers into parallel, interlaced or staggered positions, and in a direction transverse to the traveling surface 13, the entanglement of the fibers is continuous between successive rows, even though the meshes of said surface 13 are sufficiently large to permit me to use a relatively short belt 11, and even though the pressure of the water causes the whole mass to be very loosely assembled in their interlaced positions on said surface 13. The open mass of fibers thus formed is more compact next to the wire than away from it, and said mass is carried through the opening 70 into the space 43, with one or more partially curved and partially entangled layers similar to the fibers 60 and 63 clinging to it.

As stated above, in said space 43, other fibers similar to the fibers 64 become interlaced and entangled with the layers on the belt, and the process of entanglement and massing proceeds as before; but in the mean time, owing to the presence of the belt 103, layers of fibers in all respects similar to the layers 60, 63 and 64 are interlaced, entangled and massed on the traveling belt 18 from the surface 48, if the gate 30 does not close the opening 29. This second mass of fibers is carried through the opening 71 by the belt 18 in a condition similar to the first mentioned mass that passes the opening 70, and the fibers in the space 43 interlace, and become entangled with said second mass in a manner similar to that described in connection with said first mentioned mass on the surface 13. The result is, owing to the presence of the belts 100 and 103 of a relatively finer mesh, and to the parallel and staggered relations of the fibers in the space 43, a third mass of fibers are interlaced and entangled with each other on the belts 13 and 18, which have relatively short lengths and coarse meshes as compared to similar belts heretofore used. Of course, said third mass of fibers is interlaced on its sides with the finer and second masses of fibers, as well as with each of said first named masses.

As a result of the foregoing entanglements of the various fibers and the motion of the surfaces 100 and 103 of 13 and 18, the entire interlaced mass of fibers is carried through the opening 75 between the compression or compacting rolls 6 and 25, and is formed into the sheet or board 76, all as will be readily understood.

An important feature of this invention resides not only in being able to thus interlace, or entangle, the fibers in the body of the sheet with relatively short belts 11 and 18 having relatively coarse meshes, but also in being able to vary the kind, size, or class, of fibers in different portions of the sheet. That is to say, I may feed to the channel 35, one kind of fibers, which may be rela-

tively short or more expensive fibers than are those fed to the channel 40, and I may feed to the channel 45, the same class of fibers as are fed to the channel 35, or I may feed a totally different class of fibers. In other words, I may provide as many channels 35, 40 and 45, as there are different characters of fibers in the finished board, and I may place in the first channel 35 and in the last channel 45 any character of fibers I desire, whereupon the finished board will be provided with an outer layer 77 corresponding to the fibers that are fed to the channel 35, with another outer layer 78 corresponding to the fibers that are fed to the channel 45, and with one or more intermediate layers 79 corresponding to the character of the fibers which are fed to the channel 40 and to any other channels which may be located intermediate of the channels 35 and 45.

But the important feature to be emphasized in this invention is the fact that no matter how many kinds of fibers or how many layers of fibers that are present in the finished board, the fibers of each layer will be interlaced or entangled with the fibers of its adjacent layer on belts of wire cloth 11 and 18 which are much shorter than those now in use for the same output of product, and said fibers will be so interlaced that the board will not consist of separate and distinct layers somewhat like the leaves of a book, that can be peeled off, as has been heretofore the case, but its body will consist of fibers that are firmly interwoven, and its outer layers will be firmly interwoven with said body portion. I am thus enabled to produce with a comparatively inexpensive machine, a fiber board or sheet having comparatively inexpensive fibers on its interior and comparatively expensive fibers on its exterior, so that a highly ornamental appearance can be imparted to and retained on the finished product at a minimum of expense.

I do not wish to be limited to any particular character of fibers, for my invention is applicable to fibers in general. It is only necessary to float the fibers on the water to get them into parallel and staggered positions as indicated in Figure 3, and to then entangle them as is illustrated in Figure 4. The process is facilitated by the fact that the openings 37, 42 and 47 are of a less area than are the spaces 38, 43 and 48, into which the fibers are led. In other words, the fibers must pass through the opening in a comparatively close relation to each other, and they are then immediately released into a wider space, whereupon they naturally pass along with the water while spreading out and assuming the parallel relations indicated in Figure 4.

I further prefer to permit a very large proportion of the water, say 90% of the

same to escape through the opening 15, while a very much smaller proportion, say 10% escapes through the opening 29. The gates 16 and 30 are conveniently manipulated to effect this result, and by so proportioning the water, I am enabled to maintain the proper steady flows through the surfaces 13 and 18 to produce the desired result, even though the fiber coatings on said surfaces 10 may vary. But of course the proportions of water that escape through the two openings mentioned may be widely varied according to the results sought in the finished board.

The rolls 6 and 25 are readily adjusted by 15 the means illustrated to produce any desired compression in the opening 75 between said rolls, so that the fiber board may be given any desired degree of porosity. In fact, by using relatively large fibers in the channel 20 40, and relatively fine fibers in the channels 35 and 45, I am enabled to control the air spaces in the body of the board, and thereby to control its heat-insulating qualities.

The heads 36, 41 and 46, of the liquid in 25 the channels 35, 40 and 45 are so maintained that there will be a minimum tendency of liquid to flow between the spaces or chambers 38, 43 and 48. In other words, the pressures of the liquid in the last mentioned 30 spaces are maintained as nearly equal as possible, and thus a minimum tendency of the fibers to fail to interlace is secured.

It is obvious that those skilled in the art 35 may vary the details of the construction as well as the details of the process without departing from the spirit of the invention, and therefore I do not wish to be limited to the above disclosure except as may be required by the claims.

40 What I claim is:—

1. The process of interlacing fibers on an 45 endless revolving screen having meshes too large to efficiently stop said fibers, which consists in causing said fibers to assume more or less parallel positions in a direction transverse to the path of movement of said screen; causing some of said fibers to be interlaced and massed at each revolution of said screen, on a portion only of the latter; and then 50 causing the moving interlaced mass of fibers to stop and interlace with other fibers to form the desired product, substantially as described.

2. The process of interlacing fibers on an 55 endless revolving screen having meshes too large to efficiently stop said fibers, which consists in causing said fibers to assume more or less parallel positions in a direction transverse to the path of movement of said screen; 60 providing a relatively fine foraminous surface for a limited distance inside said screen, thus causing some of said fibers to be interlaced and massed at each revolution of said screen, on a portion only of the latter; and 65 then causing the moving interlaced mass of

fibers to stop and interlace with other fibers to form the desired product, substantially as described.

3. In a machine for making a fiber board 70 of interlaced fibers, the combination of a plurality of movable foraminous surfaces; a relatively short foraminous surface of a finer mesh positioned inside one of said first named surfaces; a plurality of separated channels for floating different kinds of fibers 75 to said surfaces; and causing said different kinds of fibers to interlace with each other; and means for compacting the interlaced fibers, substantially as described.

4. In a machine for making a fiber board 80 the combination of a plurality of movable foraminous surfaces; a relatively short foraminous surface of a finer mesh positioned inside one of said first named surfaces; a plurality of separated channels for conveying liquid and different kinds of fibers separately to said surfaces; and means for maintaining substantially the same hydrostatic pressure in each channel, substantially as described.

5. In a machine for making a fiber board 85 of layers of interlaced fibers, the combination of a plurality of movable foraminous surfaces; a relatively short foraminous surface of a finer mesh positioned inside one of said first named surfaces; chambers in which said surfaces are located; and restricted channels communicating with said chambers, substantially as described.

6. In a machine for making a fiber board 100 of layers of interlaced fibers, the combination of a plurality of movable foraminous surfaces; a relatively short foraminous surface of a finer mesh positioned inside one of said first named surfaces; chambers extending 105 in directions transverse to, and in which said surfaces are located; and restricted channels having openings communicating with said chambers, substantially as described.

7. In a machine for making a fiber board, the combination of an endless belt foraminous surface; a second endless belt foraminous surface; a relatively short foraminous surface of a finer mesh positioned inside 115 one of said first named surfaces; chambers adapted to float fibers to said surfaces; means to prevent the fibers in one chamber from mixing with the fibers in the adjoining chamber; means for feeding fibers to 120 said chambers; and means causing said surfaces to compact the mass of fibers fed thereto, substantially as described.

8. In a machine for making a fiber board 125 the combination of a channel for feeding fibers; a chamber communicating with said channel for floating a set of fibers and causing them to assume parallel positions; a second channel and a second chamber for floating a second set of fibers; a foraminous 130

surface adapted to move across said chambers; and a foraminous surface having a relatively fine mesh extending along a portion of the length of and inside said first named 5 foraminous surface, substantially as described.

9. In a machine for making a fiber board the combination of a pair of foraminous surfaces; a relatively short foraminous 10 surface of a finer mesh positioned inside one of said first named surfaces; means for moving said surfaces; means for adjusting said surfaces relatively to each other; and means for feeding a different kind of fiber 15 to each of said surfaces, substantially as described.

10. In a machine for making a fiber board the combination of a pair of endless belt foraminous surfaces; means for moving 20 said surfaces; means for adjusting said surfaces relatively to each other; means for regulating the amount of water flowing

through each surface; means for feeding a different kind of fiber to each of said surfaces; and a foraminous surface of a relatively finer mesh located inside of and extending along a portion only of the length 25 of each of said first named surfaces, substantially as described.

11. The process of retaining and inter- 30 lacing fibrous material on a traveling foraminous surface having openings too large to efficiently stop said material, which consists in causing the fibers of said material to assume more or less parallel positions in 35 a direction transverse to the line of travel of said surface; and also causing said fibrous material to be retained and massed on said surface by a means independent of said surface, substantially as described. 40

In testimony whereof I affix my signature.

JOHN K. SHAW.
